 U.S. Cl. 252—522

1 Claim

ABSTRACT OF THE DISCLOSURE

The ester 2,4,4-trimethyl-2-pentyl acetate is a valuable component of perfumes and perfumed products such as soaps, lotions, creams, salves, and ointments.

15

BACKGROUND OF THE INVENTION

This invention relates to perfumes and perfumed products having the unique odor or unique odor component conferred by the compound 2,4,4-trimethyl-2-pentyl acetate.

25

The ingredients are melted together on a water bath and mixed thoroughly. Thereafter, the mixture is removed from the bath and stirred until it congeals. Table I below further illustrates bases of this type. The numbers in the columns are parts by weight.

TABLE I

Ingredient	Bases											
	2	3	4	5	6	7	8	9	10	11	12	
Landolin (anhydrous)	5	5	15.6		10.4				5.5	7.5	16.8	
Paraffin wax	15			26.1								
Petrolatum (white)	50	90	76.0	10.9	89.6	100		89.5		83.2		
Mineral oil, U.S.P.	30			62.13			100					
White beeswax		5	8.3						11.0			
Carbowax 4000							40.5					
Carbowax 400							59.5			92.5		
Hydrogenated cotton seed oil												
Cetyl alcohol	5		31.2		4.16							
Stearyl alcohol				10.4								
Cholesterol							8.9			0.76		
Landolin alcohols					66		2.2			7.5	0.67	
Glyceryl monostearate									13.8			
Stearic acid								33.3		2.2		
Magnesium oleate												
1,2,6-hexanetriol									19			

The compound itself and a mode of preparation have been reported; J. Org. Chem. 28, 55-64 (1963).

50

SUMMARY OF THE INVENTION

Perfumes and perfumed products such as soaps, lotions, creams, salves, and ointments have a very desirable odor when containing, an amount according to the perfumer's art, of 2,2,4-trimethyl-2-pentyl acetate. A slightly different but still valuable odor is obtained when said compound is admixed with up to about 30 percent of the parent alcohol.

55

DESCRIPTION OF PREFERRED EMBODIMENTS

As appreciated in the perfumer's art, it is usually desirable to admix a scent agent with other perfume ingredients to provide all the properties desired in a finished scent.

60

Thus, as appreciated by a skilled perfumer, the aforementioned acetate ester having Formula I can be mixed with vehicles such as ethyl alcohol, fixatives such as ambergris, civet, musk, balsams, and benzoin. Likewise, odorous substances such as those listed on pages 555-556 of "Chemical Process Industries," Shreve, McGraw Hill Book Company (1945) can be admixed with the above acetate.

65

As readily apparent to a skilled perfumer, the compound of Formula I or perfume compositions containing same can be used to confer a pleasant odor to materials other than the above-described bases. For example, other bases which can be perfumed are those within Tables II, III, and IV of William E. Burt, U.S. Patent 3,250,677, May 10, 1966. (As with the pertinent sections of Shreve, supra, the tables of that patent are incorporated hereinabove as fully set forth.)

2

A typical perfume having the acetate of Formula I is exemplified by the perfume described on page 572 of Shreve, supra, wherein all the benzyl acetate of the Shreve formulation is substituted with 5 grams of the compound of Formula I.

To further illustrate the compositions of this invention the following ointment, salve, and cream bases are described. According to this invention, pleasantly scented bases are made by mixing the unscented bases described below with 0.001, 0.01, 0.1, and 1.0 percent by weight of the compound of Formula I, or the same weight of compound plus (based on the weight of compound) up to 30 percent of the parent alcohol.

BASE 1

A mixture having the following ingredients is prepared. All parts are by weight.

	Parts
Cholesterol	10
Stearyl alcohol	30
White wax	80
Wool fat (anhydrous)	150
White petrolatum	730

The ingredients are melted together on a water bath and mixed thoroughly. Thereafter, the mixture is removed from the bath and stirred until it congeals. Table I below further illustrates bases of this type. The numbers in the columns are parts by weight.

BASE 13

A mixture having the following ingredients is prepared. All parts are by weight.

	Parts
Petrolatum	71.2
Lanolin	11.1
Mineral oil	16.7
Sorbitan monooleate	11.1
Glycerin	11.1

When perfuming materials containing water, it may be desirable to employ the compound of Formula I (or perfume composition containing same) with a buffering agent which will tend to keep the material to be scented at a pH between 6 and 8.

It is immediately apparent to a skilled practitioner that other materials than those set forth above can be perfumed according to this invention. For example, mothballs, soaps and synthetic detergents, whether liquids, solids, powders, laundry, medicinal soaps, or toilet bars can be perfumed.

This invention can be extended to the preparation of perfumes and perfume products prepared from a mixture of highly branched octyl acetates which are produced by the acid catalyzed reaction between di-isobutylene (2,4,4-trimethyl pentene-2) and acetic acid. In most instances, the predominant product in the mixture of esters produced by this reaction is the compound of Formula I.

In summary, a preferred embodiment of this invention is a perfumed composition comprising (1) as a perfuming agent, an odoriferous amount of 2,2,4-trimethyl-2-pentyl acetate and (2) as a carrier therefor, a non-drying inert oleaginous substance having for each 100 parts by weight of said oleaginous substance from about 5 to about 30 parts of an alcohol having from 16 to about 30 carbon atoms. The oleaginous substance called for in this em-

bodiment are materials such as lanolin, paraffin wax, Petrolatum, mineral oil, white beeswax, Carbowax 4000, Carbowax 400, and hydrogenated cottonseed oil. The alcohols described in this embodiment are exemplified by cetyl alcohol, stearyl alcohol, cholesterol, lanolin alcohols, and the like. These materials and their use thereof are illustrated by Bases 1-13 defined hereinabove.

What we claim is:

1. A perfumed composition comprising (1) as a perfuming agent, an odoriferous amount of 2,4,4-trimethyl-2-pentyl acetate, and (2) as a carrier therefor, a non-drying inert oleaginous substance having for each 100 parts by weight of said oleaginous substance from about 5 to about 30 parts of an alcohol having from 16 to about 30 carbon atoms.
